UNITED STATES PATENT OFFICE.

WILLIAM EVENSEN, OF CHICAGO, ILLINOIS, ASSIGNOR TO GOSS PRINTING PRESS COMPANY, A CORPORATION OF ILLINOIS.

MACHINE FOR OPERATING UPON STEREOTYPE PLATES.

Application filed May 25, 1923. Serial No. 641,305.

The invention relates to machines for shaving flat stereotype plates and more particularly to a novel machine having both improved plate handling or positioning devices and plate shaving devices and cooperating parts.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation of a machine constructed in accordance with the invention;

Fig. 2 is a top plan of the machine shown in Fig. 1;

Fig. 3 is a greatly enlarged vertical longitudinal section of the right-hand end of Fig. 1 showing the connections between the knife drive and the actuating means for the knife carrying mechanism, and is taken substantially on line 3—3 of Fig. 8;

Fig. 4 is a transverse vertical section taken substantially on the line 4—4 of Fig. 1;

Fig. 5 is a transverse vertical section, greatly enlarged, taken substantially on the line 5—5 of Fig. 1, looking in the direction of the arrows;

Fig. 6 is a longitudinal vertical section taken substantially on the line 6—6 of Fig. 5 looking in the direction of the arrows.

Fig. 7 is a fragmentary vertical section taken on line 7—7 of Fig. 5; and

Fig. 8 is a diagrammatic elevation of the driving connections between the motor and the knife carriage.

The machine herein disclosed as the present preferred embodiment of the invention, comprises as its general features a stationary or fixed bed upon which the stereotype plate or plates to be shaved are supported face down and in proper position and a cooperating shaving knife carriage which is recip-

rocable to and fro along guideways formed by the side edges of the bed. The means for so reciprocating the carriage and thereby forcing the knife along the plate during the shaving of the plate, operates along and above the bed and directly behind the carriage and preferably at two separated points transversely of the carriage. There are preferably two such side by side carriage-actuating devices, operating simultaneously and equally on the carriage to preserve it in absolute transverse alignment in its movement along the bed and especially during the plate shaving operation.

The embodied form of this carriage operating means comprises two screw-threaded rods connected directly and relatively rotatably to the back end of the carriage, and extending rearwardly longitudinally of and directly above the bed, suitably driven reversible screw-threaded gearing being provided for actuating the screw rods.

The plate-shaving knife is suspended freely in the carriage so as to have a desirable rocking motion longitudinally of the bed. Means are provided for raising and lowering the knife relatively to the carriage and therefore relatively to the bed, to regulate or determine the thickness of the finished plate; the movable knife, however, in all positions of work being firmly backed and supported by the rigid and absolutely positioned carriage. The knife is also preferably set with its cutting edge inclined transversely of the bed so that the attack on the plate during the shaving operation is gradual and is effected somewhat diagonally of the plate throughout its progress.

A stereotype plate positioning stop mechanism is mounted on the forward end of the bed and this stop is vertically adjustable or positionable relatively to the bed, and is preferably kept always at the same relative level with respect to the shaving knife on the carriage, the stop being of such height as just to permit the making of the deepest cut which may be desired. The vertical raising and lowering and therefore positioning of the knife and stop are effected by a single mechanism which maintains them in the constant relation already described. The bed stop has its rear or plate-engaging edge preferably disposed diagonally across the bed, and preferably in the opposite direction to that in which the shaving knife is in-

clined. The stop and shaving knife both being beveled, the plate is presented to, and is operated on by, the knife in a different and more advantageous manner than if either were used alone.

Other features of the invention will be primarily set forth in connection with the following detailed description; and it will be understood that the foregoing general description and the following detailed description both are illustrative and exemplary of the invention but are not restrictive thereof.

Referring now to the embodiment of the invention shown by way of example in the accompanying drawings, the bed 1 of the machine is preferably in fixed position upon the general frame 2 which is fixed to or mounted on a pedestal or other support 3. This bed is preferably of general rectangular form and the stereotype plate or plates 2 to be shaved or trimmed are supported face downward upon the surface 4 of this table or bed. The side edges of the bed 1 are formed into guideways 5 and 6 for the knife supporting carriage 7, which is reciprocable to and fro along the bed.

The general structure of the shaving knife carriage includes guide portions 8 and 9, which are formed with recesses therein to fit the guideways 5 and 6 accurately while being freely reciprocable therealong. The body 10 of the carriage extends upwardly from the foregoing, and the details of the mounting of the shaving knife therewithin will be later described.

In the embodied form of actuating means for the carriage, there are preferably provided a plurality of actuating and guiding members engaging directly with the rear of the carriage, at separated points transversely thereof, so as to always keep the carriage in exact transverse alignment with respect to the bed and to prevent any strain or displacement thereof. As embodied, on the rear vertical face of the carriage there are formed cylindrically apertured bosses 18 and 19 within which the forward ends of screw-threaded rods 20 and 21 are bolted. The screw rods 20 and 21 extend rearwardly along and above and parallel with the surface 4 of the bed. Guards may be placed about the screw-shafts 20 and 21, and for this purpose pipes 25 and 26 are shown enclosing the screw shafts and having their flanges bolted to the bearings for the screw-shafts. The power is thus applied directly to the carriage at the rear thereof, and directly in line with its movement, and within the two guideways for the carriage. There is, therefore, no chance for any strain in the head to distort the cut, as the power is applied in line directly behind the carriage with the thrust entirely in the forward direction.

In the embodied form of actuating means

for the foregoing mechanism, gear wheels 23 and 24 are mounted free to rotate on the screw shafts 20 and 21, respectively, these gear wheels being provided with spur gear teeth. Integral and concentric with the gear wheels 23 and 24, respectively, are internally screw-threaded bushings 31, which are screw threaded onto the screw shafts 20 and 21, respectively.

The sleeves 31 have smooth external cylindrical surfaces, and are rotatably mounted in pedestals or brackets 32, respectively, whereby the gear wheels 23 and 24 with their corresponding sleeves or bushings 31 may be rotated in either direction to correspondingly propel the knife bearing carriage forwardly or backwardly along the bed. The gear wheels 23 and 24 are provided with thrust bearings in the ends of the respective pedestals or journal blocks 32. The flat sides of the gears 23 and 24 bear against roller bearings carried by the blocks 32 and 37; the rollers of the roller bearings are indicated at 35. On the opposite or front side of the gear wheels 23 and 24 they are provided with concentric sleeves 36 which loosely surround the respective screw shafts and which are journaled, respectively, in bearing blocks 37.

Referring now to the embodied form of driving means for the carriage-operating screw shafts, and their screw feeding gear wheels just described, a motor 44 is shown mounted on a bracket 45, carried on the machine frame. On the motor shaft is a belt-driving pulley 46, over which runs a belt 47, the belt running also over a driven pulley 48, fixed on a shaft 49. Mounted on shaft 49, to rotate therewith, is a double-action friction clutch 50, which may be of any suitable or convenient form.

Loosely mounted on shaft 49 at one side of the friction clutch and cooperating therewith is a gear wheel 51. Likewise, on the opposite side of the friction clutch 50, loosely mounted on shaft 49, is a gear wheel 52, also adapted to be driven by the clutch 50. Meshing with the gear wheel 51 is a gear wheel 54, fixed on a shaft 55, which shaft is journaled at 56 and 57 on the machine frame. Gear wheel 54 meshes with both gear wheels 23 and 24, previously described. Gear wheel 52 meshes with an idler gear wheel 59, shown in Fig. 8. The idler 59 in turn meshes with a gear wheel 64, which is fixed on shaft 55 already described.

The manner of operation of the hereinbefore described mechanism is substantially as follows:

The motor 44 may be regarded as continuously running, and the shaft 49 will rotate continuously therewith, the double acting clutch 50 rotating with its shaft 49. When the clutch is in neutral position, the mechanism just described will run idle. When

the friction clutch 50 is brought into driving engagement with gear wheel 51, gear wheels 23 and 24 are driven through gear wheel 54 to advance the knife-bearing carriage, that is, to move it toward the left in Figs. 1 and 2.

Considering the clutch 50 again in neutral position, if the clutch be brought into driving engagement with the gear 52, it will then through the idler 59 and gear wheels 64 and 54 rotate gear wheels 23 and 24 in the opposite direction, and will move the knife bearing carriage backwardly or to the right in Figs. 1 and 2. When the carriage is being driven forward, gear 52 will rotate idly on shaft 49 as it is out of engagement with the friction clutch 50, and when the carriage is being driven backward, gear wheel 51, being out of engagement with the clutch 50 will rotate idly on the shaft 49.

Referring now to the embodied means for mounting and positioning the shaving knife upon its carriage, a wedge shaped or beveled slide 70 is mounted in the main body 25 of the carriage to slide horizontally and transversely thereof. For this purpose, it is provided with a T head, having guiding projections 71 and 72 extending along the upper edges thereof. These guiding projections, respectively, run in horizontally disposed guideways 73 and 74 formed one in the body of the carriage and the other in the front plate 75, which plate is fastened to the carriage in suitable manner, as 30 by bolts 76.

The sliding piece 70 is internally apertured to receive its actuating shaft 77, which shaft has a screw-threaded portion 78 engaging with an internally screw-threaded portion 79, formed within the member 70. This shaft 77 is journaled at 40 80 and 81 in the sidewalls of the upwardly extending portion of the carriage. The shaft is shouldered at 83 to longitudinally position it in its bearings in the carriage, as shown in Fig. 5. A hand wheel 84 is fixed to the shaft on the outside of the carriage with the hub 85 of the hand wheel bearing against the outer wall of the carriage structure.

At its opposite end, shaft 77 projects outwardly from the side of the carriage, and fixed thereon is a bevel gear 86, the hub thereof likewise forming a bearing surface 55 against the carriage structure, to maintain the shaft 77 in longitudinal position. In sliding engagement with the transversely movable wedge member 70, is a vertically slidable member 90, interlocking slidable connection between the two being effected by the hook-like members 91 and 92, as shown in Fig. 6. The member 90 is vertically slidable between the solid back plate of the upwardly projecting part of the carriage structure, and the front plate 75 already de-

scribed. The side edges or ends of the vertically slidable member 90 are in close slidable engagement with the surfaces 96 and 97 of the side walls of the carriage, which also serve to guide the member 90 and prevent any possible cant or deflection thereof.

The shaving knife 98 is preferably mounted upon this positioning structure so as to swing freely backwardly upon the return motion of the carriage. As embodied, the knife 98 is mounted on a carrying block 99, which block is provided at either end thereof with apertured supporting blocks or ears 105 and 106, which are fixed to the block by screws 107 and 108. A shaft 109 passes loosely through the aperture in the blocks or ears 105 and 106, the shaft being fastened to and supported by the sliding member 90 by suitable means such as screws 112.

Means are provided for adjustably positioning the knife upon its holder or carrier block 99, and preferably to adjust it absolutely to a true position horizontally with reference thereto and thereby to the supporting bed 4 and the stereotype plates thereon. As embodied, there is provided at the bottom and at either side of the knife bearing block two forwardly extending supports or blades 114 which are at a definite predetermined distance above the support 4. The bottom edge of the knife 98 rests upon these supports.

A plurality of slots 115 are formed in the knife 98, and clamping screws 116 project loosely through these slots and are screw-threaded into the knife carrying block 99, as best appears from Fig. 6. A plurality of positioning screws 117 are screw-threaded into lugs 118 projecting horizontally forwardly from the knife-carrying block 99, the tips of these screws bearing against the top of the knife. Thus the screws 117 will press the knife firmly home to its seat on the supports 114, and the clamping screws 116 will hold the blade in position with its cutting edge horizontally true and parallel with the bed surface 4.

The mechanism just described operates substantially as follows:

If the hand wheel 84 be rotated in either direction, the wedge shaped member 70 will travel horizontally along shaft 77, sliding in its guideway, either to the right or to the left in Fig. 5. Due to the interlocking of the member 70 with the member 90, as shown at 91 and 92, the member 90 will move either upwardly or downwardly in its guideways in the carriage, corresponding to the horizontal movement in either direction of the member 70, as just described. This will raise or lower the shaving knife 98 with respect to the surface 4 of the bed, upon which surface the stereotype plate or plates to be shaved rests. An indicator 87 is pivoted at 125

89 to the casing and is actuated by a pin 88 carried by member 90, which pin is movable in a slot 88^a on an arm 87^a rigid with the indicator 87. This will cause the indicator 5 hand to move along the scale 89^a and enable the operator to accurately regulate the thickness of the shaved plate.

As the carriage travels forwardly, as during the shaving of the plate or plates, when 10 the knife 98 engages the work, the block 99 is pressed backwardly about its pivotal bearing on the shaft 109 and the back surface 124 of the knife-bearing block bears directly and firmly against the flat and solid surface 125 15 of the carriage. Thus there can be no give or yield as the machine operates, as in this position the knife is as though it were integral with the carriage. When the carriage is traveling backwardly the knife is free to swing or rock forwardly, that is to the left 20 in Fig. 6, should it encounter any obstruction.

In accordance with one feature of the invention, a stop for holding or positioning the 25 stereotype plate or plates to be shaved is provided, which is shaped or positioned to present said plate or plates diagonally with respect to the shaving knife and preferably also with respect to the bed 1.

30 It is also usually preferable that the positioning surface or side of the stop shall be inclined reversely to the direction of inclination of the shaving knife, as shown in Fig. 1.

35 According to one feature of the invention, this positioning stop mechanism for the stereotype plate to be operated on moves upwardly and downwardly in permanent fixed relation with respect to the shaving knife as the knife is moved toward or away 40 from the bed, so that the stop is just clear of the cut of the knife as it finishes shaving the plate and passes over the stop. In the present embodiment, these two features of 45 the invention are incorporated into the same mechanism.

Accordingly, a block or stop support 130 is mounted for to and fro vertical movement in a recess in the forward end of the machine bed, the side edges 131 and 132 being in accurate slidable engagement with the side walls of the aperture in the machine bed, to aline and guide the stop bearing block. The block 130 extends upwardly above 55 the surface of the bed 1, and the stop proper is preferably a plate 134 removably fixed in the top of the block 130 and extending horizontally rearwardly therefrom, and having a beveled edge 135 against which the stereotype plate π is positioned as it rests upon the surface 4 of the bed 1.

60 The stop plate 134 is removably but accurately held in position on its supporting block 130 as by a slidable dove-tail joint 129 as shown in Fig. 1. When a very large

stereotype plate is to be shaved there may not be room to place it diagonally, in which case stop plate 134 may be removed and the plate placed squarely against stop 130.

Referring now to the embodied form of 70 means for raising and lowering the shaving knife and this work stop together, a shaft 146 is journaled in brackets 147 and 148, which extend outwardly from the side of the reciprocating carriage. A bevel gear 150 is 75 fixed on shaft 146, and is in mesh with the bevel gear 86 already described. At its opposite end, there is fixed to shaft 146 a bevel gear 151, which meshes with a bevel gear 152. Bevel gear 152 is splined on a shaft 80 153 so that they rotate together, the gear being slidable along the shaft.

Shaft 153 is journaled in brackets 154 and 155, which are fixed to and extend outwardly from the side of the machine frame. 85 The hub of gear wheel 152 is journaled in bracket 148 which causes it to slide along shaft 153 and to keep in mesh with the bevel gear 151 on shaft 146. Fixed to the forward end of shaft 153 is a bevel gear 156, which 90 meshes with a bevel gear 157 which is fixed on a shaft 158. Shaft 158 is journaled in brackets 159 and 160 fastened to the machine frame.

95 Fixed on shaft 158 is a bevel gear 161 which meshes with a bevel gear 162 which latter is fast on a shaft 163. Shaft 163 is journaled in a lug 164, formed on the supporting pedestal 3. A collar 165 maintains the shaft in its position in its bearing. The 100 upper end of shaft 163 is provided with a screw-thread 166 which is screwed into an internally screw-threaded aperture 167, formed in the stop carrying block 130. A hand wheel 168 is fixed to shaft 163.

105 A suitable automatic throw-off or stop motion is preferably provided which may be of any desired or convenient form. As shown, clutch 50 has an operating lever 170, which is pivoted at 171 on the frame. The lever at 110 its outer end has a pivot connection 172 with a longitudinally slidable rod 173. A pivoted handle 174 slides rod 173 to throw in clutch 50 either way. Stop pins 175 and 176 are fixed to rod 173, and a lug 177 on the 115 knife carriage engages therewith at either end of the carriage travel to automatically throw out the clutch.

120 The drive for the knife carriage is directly behind the carriage, and acts thereon from directly behind at two well separated points, the drive itself being in positive alignment in the direction of travel of the carriage. The carriage has also rigid and ample guideways upon the bed itself. Thereby absolute 125 rigidity and accuracy in the position and travel of the carriage is insured. The knife is mounted so that while it is free to swing for clearance it is always accurately in position as to thickness and is firmly and accu- 130

rately backed directly against the rigid structure of the carriage during the shaving operation. The vertically adjusting mechanism for the shaving knife is backed and supported in the same manner.

6 The knife and stop mechanism are likewise kept in accurate and permanent relative position with respect to each other through all changes in the depth of the cut, 10 or thickness of the shaved plate, by means of the single mechanism for operating to simultaneously position both the knife and stop. The beveled stop also presents the work in the most advantageous way to the knife and 15 increases the angularity between the work and the knife whereby it is possible to shave a very small plate perfectly flat, and because the knife leaves the work so gradually it is further possible to lay a number of small 20 plates one behind the other and to shave all of them successively at one operation of the machine and secure a smooth, uniform and accurate cut in all the plates.

When the stop is placed at any angle and 25 the knife is also placed at a small angle, there is very little side thrust, the cutting is in a straight line forward, and presses the work firmly against the stop. Where a very large plate is to be shaved, the removable 30 beveled portion of the stop may be removed by reason of the connection already described, and the full space up to the portion of the stop mechanism which works through the bed plate may be utilized and also with 35 a large plate if placing the plate against the angled stop will prevent its passing within the opening at the bottom of the carriage between the guides, the straight part of the stop may be employed.

40 The invention in its broader aspects is not limited to the specific mechanisms shown and described but departures may be made therefrom within the scope of the accompanying claims without departing from the 45 principles of the invention and without sacrificing its chief advantages.

What I claim is:—

1. A machine for shaving stereotype printing plates including in combination means 50 for supporting and positioning a stereotype plate, a traveling knife carriage having a rigid wall, a shaving knife swingably mounted on the carriage, and adapted to press firmly against said rigid wall during the 55 shaving operation and means for effecting relative reciprocatory movement between the stereotype plate and the shaving knife.

2. A machine for shaving stereotype printing plates including in combination means 60 for supporting and positioning a stereotype plate, a traveling knife carriage having a rigid wall, a shaving knife hingedly mounted on the carriage, and adapted to press firmly against said rigid wall during the 65 shaving operation, a plate stop movable

simultaneously with the positioning of said knife, and means for effecting relative reciprocatory movement between the stereotype plate and the shaving knife.

3. A machine for shaving stereotype printing plates including in combination a support for a stereotype plate to be shaved, a shaving knife variably positionable relatively to the plate to regulate the amount of the cut and a stop for the plate movable 75 simultaneously with the positioning of the knife.

4. A machine for shaving stereotype printing plates including in combination a support for a stereotype plate to be shaved, a 80 shaving knife variably positionable relatively to the plate to regulate the amount of the cut, a stop for the plate movable simultaneously with the positioning of the knife and connections between the knife and stop 85 for maintaining them in the same relative position.

5. A machine for shaving stereotype printing plates including in combination a stereotype plate supporting bed, a reciprocable 90 carriage and a shaving knife mounted thereon, a stop for positioning the plate on the bed, the bed and knife being relatively movable for effecting cuts of different depths and means for maintaining the knife and 95 stop in the same relative position.

6. A machine for shaving stereotype printing plates including in combination a stereotype plate supporting bed, a reciprocable carriage and a shaving knife mounted thereon, a stop for positioning the plate on the bed, the bed and knife being relatively movable for effecting cuts of different depths and means operating automatically to maintain 100 the knife and stop in the same relative position.

7. A machine for shaving stereotype printing plates including in combination a fixed stereotype plate supporting bed with guideways formed thereon, a reciprocable carriage 110 traveling on the guideways and a shaving knife mounted thereon, a stop for positioning the plate on the bed, the bed and knife being relatively movable for effecting cuts of different depths and means for maintaining 115 the knife and stop in the same relative position.

8. A machine for shaving stereotype printing plates including in combination a fixed stereotype plate supporting bed with guideways formed thereon, a reciprocable carriage traveling on the guideways and a shaving knife mounted thereon, a stop for positioning the plate on the bed, the bed and knife being relatively movable for effecting cuts of different depths and means operating automatically to maintain the knife and stop 120 in the same relative position.

9. A machine for shaving stereotype printing plates including in combination a stereo- 125

type plate supporting bed and a knife carriage relatively movable with respect to each other, and an oblique stop on the bed for presenting a stereotype plate obliquely to the knife on the carriage to be shaved thereby.

10. A machine for shaving stereotype printing plates including in combination a stereotype plate supporting bed and a knife carriage relatively movable with respect to each other, a knife on the carriage with its cutting edge set obliquely to the direction of said movement, and an oblique stop on the bed for presenting a stereotype plate obliquely to the knife on the carriage to be shaved thereby.

11. A machine for shaving stereotype printing plates including in combination a stereotype plate supporting bed, a knife carriage, and a plate stop adapted to present a plate to the knife either squarely or obliquely to the knife.

12. A machine for shaving stereotype printing plates including in combination a stereotype plate supporting bed, a knife carriage, and a plate stop having detachable parts and thereby adapted to present a plate to the knife either squarely or obliquely to the knife.

13. A machine for shaving stereotype printing plates including in combination a plate supporting bed, a carriage, and a mounting thereon for the knife, means for relatively variably positioning the knife mounting and carriage to effect shaving cuts of different depths, and knife blade abutment stop means for positively positioning the knife on its mounting.

14. A machine for shaving stereotype printing plates, including in combination a shaving knife, a mounting block for the shaving knife, knife edge abutment means carried by the mounting block for determining the accurate placement of the shaving knife thereon, and means for clamping the knife to the block.

15. A machine for shaving stereotype printing plates, including in combination a shaving knife, a mounting block for the shaving knife, means carried by the mounting block and engageable with the edge of the knife, for determining the accurate placement of the shaving knife thereon, and means for clamping the knife to the block.

16. A machine for shaving stereotype printing plates, including in combination a shaving knife, a mounting block for the shaving knife, a pair of supports carried at the ends of the mounting block and engageable under the knife near each end thereof, for determining the accurate placement of the shaving knife on the mounting block, and means for clamping the knife to the block.

17. A machine for shaving stereotype printing plates, including in combination a shaving knife, a mounting block therefor, a support carried by the mounting block against which the knife is adapted to seat for determining the accurate placement thereof, means for pressing the knife against said support, and means for clamping the knife to the mounting block.

18. A machine for shaving stereotype printing plates, including in combination a stereotype plate, supporting bed, a traveling knife carriage, means for reciprocating the knife carriage over the plate supporting bed, knife supporting means having an inclined bearing surface, and a transversely movable wedge member engageable with said inclined bearing surface for moving the knife supporting means.

19. A machine for shaving stereotype printing plates, including in combination a stereotype plate supporting bed, a traveling knife carriage, means for reciprocating the knife carriage over the plate supporting bed, knife supporting means vertically movable in the knife carriage, and a transversely movable wedge directly above the knife supporting means and engageable therewith for causing it to rise and fall for adjusting the position of the cutting knife.

20. A machine for shaving stereotype printing plates, including in combination a stereotype plate supporting bed, a traveling knife carriage, means for reciprocating the knife carriage over the plate supporting bed, and means for vertically adjusting the knife, comprising two members having obliquely disposed, L-shaped, interengaged elements, and means for moving one of said members transversely.

In testimony whereof, I have signed my name to this specification.

WILLIAM EVENSEN.
